US00D797147S

(12) **United States Design Patent** (10) **Patent No.:** **US D797,147 S**
Koo et al. (45) **Date of Patent:** **** Sep. 12, 2017**

(54) **DISPLAY SCREEN OR PORTION THEREOF WITH ICON**

(71) Applicant: **Samsung Electronics Co., Ltd.**, Suwon-si (KR)

(72) Inventors: **Bonheon Koo**, Incheon (KR); **Kyungchui Oh**, Seoul (KR); **Kyungsik Yoon**, Seoul (KR); **Hyun Yeul Lee**, Seoul (KR)

(73) Assignee: **SAMSUNG ELECTRONICS CO., LTD.**, Suwon-si (KR)

(**) Term: **15 Years**

(21) Appl. No.: **29/573,206**

(22) Filed: **Aug. 3, 2016**

(30) **Foreign Application Priority Data**

Jun. 3, 2016 (KR) 30-2016-0027211

(51) LOC (10) Cl. **14-04**

(52) U.S. Cl.

USPC **D14/492**

(57) **CLAIM**

The ornamental design for a display screen or portion thereof with icon, as shown and described.

DESCRIPTION

FIG. 1 is a front view of a display screen or portion thereof with icon showing our new design according to a first embodiment;

FIG. 2 is a front view of a display screen or portion thereof with icon showing our new design according to a second embodiment;

FIG. 3 is a front view of a display screen or portion thereof with icon showing our new design according to a third embodiment;

FIG. 4 is another front view of the first embodiment, shown with a different environment;

FIG. 5 is another front view of the second embodiment, shown with a different environment; and,

FIG. 6 is another front view of the third embodiment, shown with a different environment.

The outer perimeter, illustrated by a pair of broken lines in FIGS. 1-3 and by broken lines in FIGS. 4-6, represents a display screen or portion thereof and forms no part of the claimed design.

1 Claim, 6 Drawing Sheets
